CLAIM

The ornamental design for a camera battery, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, rear, left side perspective view of a first embodiment of a camera battery, showing our new design in a first configuration;

FIG. 2 is a top view thereof;

FIG. 3 is a bottom view thereof;

FIG. 4 is a left side view of the camera battery, shown in a second configuration;

FIG. 5 is a right view thereof;

FIG. 6 is a front view thereof; and

FIG. 7 is a rear view thereof.

FIG. 8 is a top, rear, left side perspective view of a second embodiment of the camera battery;

FIG. 9 is a top view thereof;

FIG. 10 is a bottom view thereof;

FIG. 11 is a left view thereof;

FIG. 12 is a right view thereof;

FIG. 13 is a front view thereof; and,

FIG. 14 is a rear view thereof.
